[57] ABSTRACT

An improved set of upper and lower dentures which are expandable, so that upon a slight pressure, when the dentures are compressed in the mouth, there is a greater holding power for retaining the dentures properly in place.

EXPANDABLE DENTURES

This invention relates generally to dentures.

It is generally well known that a conventional denture is often uncomfortable and troublesome in being properly retained by a wearer, so that this situation is therefore in want of an improvement.

Accordingly, it is a principle object of the present invention to provide an improved denture wherein upon a slight pressure, when the denture is compressed in the mouth, there is a greater holding power of the denture to the wearer.

Another object is to provide an expandable denture wherein the principle of the present invention is readily applicable to both upper and lower dentures.

Other objects are to provide an expandable denture which is simple in design, inexpensive to manufacture, rugged in construction, easy to use and efficient in operation.

Further objects of the invention will appear as the description proceed.

To the accomplishment of the above and related objects, my invention may be embodied in the form illustrated in the accompanying drawings, attention being called to the fact, however, that the drawings are illustrative only, and that changes may be made in the specific construction illustrated and described within the scope of the appended claims.

FIG. 1 is a diagram representing a conventional upper denture.

FIG. 2 is a diagram of an upper denture that incorporates the present invention.

FIG. 2A is a view in direction 2A—2A of FIG. 2.

FIG. 3 is a diagram of a conventional lower denture.

FIG. 4 is a diagram of a lower denture that incorporates the present invention.

FIG. 5 is a perspective view of a lower denture shown incorporating the present invention.

FIG. 6 is a perspective view of an upper denture shown incorporating the present invention.

Referring now to the drawing in detail, the reference numeral 10 represents diagrammatically in FIG. 1 a conventional upper denture such as is presently being made without the benefit of the present invention, and which is shown to include a horse shoe shaped row of teeth 11 and a mouth roof pallet 12. In FIG. 3 a conventional lower denture 13 is diagrammatically represented to include generally horse shoe shaped row of lower teeth 14. As shown by dimension *a* in FIG. 1 and by dimension *b* in FIG. 3, the distance between the teeth centerline on opposite ends is fixedly constant and does not change at any time.

In the present invention, an upper denture 15 shown diagrammatically in FIG. 2, and a lower denture 16 shown diagrammatically in FIG. 4 show corresponding rows of teeth 11 and 14 respectively, wherein dimensions *A* and *B*, corresponding to dimensions *a* and *b* of FIGS. 1 and 3, are not constant but are changeable due to the dentures 15 and 16 being expandable.

In the present invention, the upper denture 15, has a Y-shaped cut 17 starting at a rear edge of the pallet 18 and is equally spaced from the center line of a median line running down toward the front of the denture, thus Y-shaping any distance along toward the front from the

third molar to the cupid. The Y-cut is such so that when the denture is compressed where the center line of the gun channel lines up with the center line of the gum, the cut 17 is then completely closed. At the 5 forked ends of the Y-cut 17, an acrylic resin 19 has a workable modulus of resilience and toughness with elastic limit so to retain its character under compression and expansion. The normal denture material is beveled in such a way that the pliable denture material 10 laps against the gum, or the pliable denture material is pre-stretched so that it would not lap against the gum when in both cases the denture is compressed.

The lower denture 16 is provided with an acrylic resin 20 which also has a workable modulus of resilience and toughness as well as elastic limit so to retain its character under compression and expansion. This acrylic resin can be situated anywhere between the cupid and the first bicuspid going to the back of the denture to between the second and third molar. As above 15 described for the upper denture, the normal denture material is bevelled so the pliable material laps against the gum, or is pre-stretched. Teeth 14 are formed upon a horse-shoe shaped base, as shown in FIG. 5.

An acrylic resin 21 is of a softer texture than is used 25 normally in dentures in order to minimize abrasion. The acrylic resin 21 protrudes slightly in view that it will give, as is clearly indicated in the diagrammatic FIG. 4.

In FIGS. 5 and 6 the pair of lower and upper dentures 30 16 and 15 are shown in true appearance by incorporating the features that were diagrammatically indicated in FIGS. 2 and 4 respectively.

While certain novel features of my invention have been shown and described and are pointed out in the 35 annexed claims, it will be understood that various omissions, substitutions, and changes in the forms and details of the device illustrated and in its operation can be made by those skilled in the art without departing from the spirit of the invention.

What I claim as new and desire to secure by Letters Patent is:

1. In a pair of expandable dentures, the combination of an upper and lower denture, each of which incorporates means for resilient expansion and contraction in 45 a transversely sideward direction so that a dimension between a centerline of teeth at each opposite end thereof is changeable; said upper denture consisting of a horse-shoe shaped row of teeth and a mouth roof pallet, said pallet having a rear edge aligned with a rear 50 end of said end teeth, said pallet having a straight slit portion that starts at a center of said rear edge and extends forwardly for a substantial portion of said pallet and which at its forward end communicates with a pair of slit portions that extend in opposite angularly rearwardly directions, each of said pair of slit portions being arcuate in configuration, the terminal ends of 55 said pair of slit portions communicating with a portion of said pallet which is made of an acrylic resin having a workable modulus of resistance and toughness with elastic limits; and said lower denture consisting of a 60 horse-shoe shaped row of teeth on a same shaped base, an inner side of the opposite ends of said base being made of a like said acrylic resin and which at its forward end extends transversely across said base.
